MARGIN GLUING MACHINE

Charles F. Schaefer, Norwalk, Conn.

Application November 2, 1946, Serial No. 707,418

8 Claims. (Cl. 91—50)

1

This invention relates to improvements in margin gluing machines and is particularly directed to a machine for applying a strip or stripe of glue or other adhesive to the margin or edge of a sheet of material.

One of the objects of the present invention resides in the provision of a machine of the character indicated which has a minimum number of parts and which can be readily and accurately assembled.

Another object of this invention is the provision of a machine having an adhesive or glue tank which is readily removable for cleaning, repair or replacement.

Another object of this invention resides in the provision, in a machine of the character indicated, of a glue tank which removably supports the tank roller whereby that roller can be readily removed with the tank and from the tank.

A further object of the present invention resides in a novel mount or support for the glue tank, whereby the tank is resiliently supported, and which in turn provides a resilient support for the tank roller.

A still further object is the provision of heating means for the tank, which, while separate from, is always maintained in contact with, the tank bottom and is moved with the tank during adjustment of the latter.

A further object of the present invention resides in readily operable means for adjusting the position of the tank.

Other and further objects of the present invention will be manifest from the following description and the accompanying drawings in which drawings:

Fig. 1 is a side elevational view of the machine of the present invention;

Fig. 2 is a rear elevational view thereof;

Fig. 3 is a fragmentary end view of the pivoted ends of the glue tank and heater;

Fig. 4 is a fragmentary side view of the tank and heater supporting means;

Fig. 5 is a plan view of several parts of the machine;

Fig. 6 is an enlarged fragmentary view partly in section of one of the tank supports;

Fig. 7 is a view similar to Fig. 6, showing a modified form of one of the tank supports; and

Fig. 8 is a view taken substantially on line 8—8 of Fig. 6.

Referring to the drawings in detail the machine shown in Figs. 1 and 2 comprises a bed or support 10 having a transversely extending vertical partition 12 located substantially centrally of the bed of the machine.

A driving motor 14 is mounted on the machine bed and is provided with a pulley 16 over which a drive belt 18 passes. The drive belt passes over a larger pulley 20 carried by a shaft 22 in a jour-

2

nal 24 supported on a standard 26. The inner end of the shaft 22 carries a pinion 28 which is in mesh with a gear 30. The gear 30 is in mesh with a pinion 32 on stub shaft 34 which carries a pinion 36 at its other end, the latter pinion drives pinions 38 and 40 on shafts 42 and 44 respectively.

Feeding rollers 46 and 48 are fixed on the shafts 42 and 44 respectively, and normally contact a gluing roller 50. A sheet of material 52 to be glued is supported by a guide 54 and passed between the feed rollers and the gluing roller. The latter roller normally contacts a tank roller 56.

The tank roller 56 has a pair of stub-shafts 58 carried in brackets 60 mounted in open bearing on either side wall of a glue tank 62. These brackets each have a scraper member 64 adapted to contact the end of the roller to remove excess glue therefrom and prevent the same from contacting the brackets. It will be noted that the brackets and scraper members are spaced inwardly from the side walls of the tank whereby excess glue removed by the scrapers will be returned to the tank whereby to prevent it from flowing over the side walls of the tank and interfering with the open bearings thereon.

The tank is supported at one end by depending legs 66, the lower ends of which are grooved, as shown in Fig. 8, and rest upon rounded sections of a cross bar 68. The cross bar is supported at each of its ends in a standard 70 provided with compression springs 72 on which squared end 74 of the bar rests. An adjusting screw 76 is provided in a threaded bore at the top of the standards, whereby the height of the bar 68 can be adjusted manually.

The other end of the tank is supported on an eccentric member 80 mounted on a shaft 82 having one of its bearings in the partition 12 and its other bearing in a journal 84. Integral with or secured to the shaft of the eccentric member 80 is a quadrant 86 provided with a gripping projection or handle 88 whereby the eccentric can be rotated to several positions within 180 degrees.

The quadrant has an arcuate slot 90. A locking member is provided for the quadrant in the form of a screw extending through the slot 90 into a threaded bore in the partition 12. The other end of this screw has a knurled knob 92 to facilitate turning of the screw into the partition 12 whereby the knob will engage and lock the quadrant and consequently the eccentric member in adjusted position. The rear end of the tank is supported on the eccentric member 80 in such a manner that counterclockwise and clockwise rotation of the quadrant and consequently the eccentric member will result in the raising or lowering respectively of the rear end of the tank causing the same to pivot on the cross bar 68.

It will be appreciated that as the rear end of

the tank is raised and lowered in the manner described the tank roller carried by the tank will be adjusted relative to the gluing roller. It will also be appreciated that, by reason of the resilient mounting of the tank, the tank roller will likewise be resiliently mounted to compensate for movement of the tank roller away from the gluing roller in the event lumps of glue, pieces of cardboard or other foreign matter in the glue, pass between these rollers. The resultant separation of the 10 rollers to permit such passage will thereby automatically be compensated for without any deleterious effect on the rollers or roller bearings.

The bearings for the shafts of the feed rollers, as well as the feed roller pinions 32, 36, 38 and 40, are carried in a bracket 96 supported on one end of lever means. The lever means comprises an arm 98 one end of which fits into a socket 100 in the bracket 96 and the other into a socket member 102 pivotally mounted on the partition 12. When the machine is being assembled the lever means is set in position and the bracket 96 so positioned in contact with the gluing roller 50 that the feed rollers 46 and 48 are in exact parallel alignment with the gluing roller, and so that the pinion 32 will properly mesh with the gear 30. When this alignment and meshing has been effected, the lever means is then secured in position by tightening set screw 104 in the socket 100 and set screw 106 in socket 102. Thereafter, if desired, permanent pins may be substituted for the set screws.

The advantages of the lever means just described over levers cast in one piece, as in prior machines of this character, will readily be appreciated. When the arm is made in one piece, as in prior structure, unless the holes for the pivot stud and bearing holes for the feed rollers are drilled and machined with extreme accuracy, spoilage of parts may result during manufacture of the machine. With the lever means of the present invention there is considerable saving in costly machining operations, in that no pre-formed holes are required, and the lever means, pinions and feed rollers fit with optimum accuracy when the machine is assembled.

When the lever means has been properly positioned, as above described, contact between the feed rollers and the gluing roller can thereafter be adjusted by means of the screw 108.

The drive for the tank roller 56 is from the driven gear 30, pinion 110, which is in mesh therewith, and which is keyed to shaft 112 on the inner end of which is keyed a pinion 114 in mesh with a gear 116 on the tank roller shaft.

An electric heater 130 for the tank is shown in Fig. 4. This heater comprises a housing 132 for a heating element 134. One end of the housing has a projecting portion 136 at each side thereof. The projecting portions are in the form of hooks 138 which fit over the cross bar 68 for pivoting thereon. The other end of the heater has a flat platform 142 which rests on the eccentric member 80 and which supports one end of the tank 62.

The heater housing is preferably made of sheet metal suitably insulated on its nether side.

As will be seen from Fig. 4, the heater is supported independently of the tank so that it will not interfere with the removability of the tank, yet it will be raised and lowered by the eccentric member 80 and the adjustable cross bar 68 during the raising and lowering of the tank.

The modified form of support for the tank shown in Fig. 7 is somewhat similar to that shown in Fig. 6. In the modified form, however, there

is no cross bar, the tank in this form being supported directly on vertical rods 120, at each corner of one end of the tank, these rods each having a pointed lower end adapted to rest in a conical depression 122 in the bed of the machine. The adjustment of the tank in the modified form is accomplished by turning collars 124 and 126 on the threaded ends, respectively, of the rod 120. In this modified form, as in the preferred form, the tank is resiliently mounted in springs 128. When the heating means are employed with this modified form the same may be bolted directly to the tank.

From the foregoing it will be seen that the present invention provides a machine for coating sheet material of varying thickness, such as cardboard, leather, shoe soles, paper, cloth and the like; the machine being adjustable to accommodate each sheet by means of the adjusting screw 108, the manipulation of which will move the feeding roller bracket 96, and consequently the feeding rollers into any desired adjusted position relative to the gluing roller.

It will also be seen that the present invention provides a machine having a minimum number of parts, which are readily assembled, adjusted and disassembled.

While I have illustrated and described certain embodiments of my invention it is to be understood that I do not wish to be limited to such embodiments, as obviously various changes and modifications may be made therein without departing from the spirit and scope of my invention.

What I claim is:

1. In a gluing machine of the class described, the combination of a base, a glue tank, a tank roller mounted on said tank, a gluing roller disposed in close proximity to said tank roller to receive glue therefrom, a feed roller in contact with said gluing roller, supporting means for said feed roller, means for pivotally mounting one end of said tank on said base, and means on said base for adjusting the height of the other end of said tank, said feed roller supporting means including an elongate arm pivotally mounted on said base, and means for varying the effective length of said arm.
2. In a gluing machine of the class described, the combination of a base having a stop thereon, 50 a glue tank, a tank roller mounted on said tank, a gluing roller disposed in close proximity to said tank roller to receive glue therefrom, a feed roller in contact with said gluing roller, supporting means for said feed roller mounted on said base above said tank, means for pivotally mounting one end of said tank on said base, and means on said base for adjusting the height of the other end of said tank, said feed roller supporting means including an elongate arm and an adjustable 55 member on said arm for engaging said stop.
3. In a gluing machine of the class described, the combination of a base, a glue tank, a tank roller mounted on said tank, a gluing roller disposed in close proximity to said tank roller to receive glue therefrom, a feed roller in contact with said gluing roller, supporting means for said feed roller mounted on said base, means for pivotally mounting one end of said tank on said base, means on said base for adjusting the height 60 of the other end of said tank, and a heater unit beneath said tank having one end supported by said means for pivotally mounting said tank and having its other end supported by said tank height adjusting means, said tank being 65 movably mounted on said heater unit and its 70 75

means for pivotally mounting one end thereof.

4. In a gluing machine of the class described, the combination of a base, a glue tank, a tank roller mounted on said tank, a gluing roller disposed in close proximity to said tank roller to receive glue therefrom, a feed roller in contact with said gluing roller, supporting means for said feed roller mounted on said base, means for pivotally mounting one end of said tank on said base, and means on said base for adjusting the height of the other end of said tank, said last mentioned means including a shaft journalled on said base, a lever on said shaft for effecting the height adjustment, manually operable means on one end of said shaft for rotating said shaft to operate said lever, and means associated with said manually operable means for securing the same to retain said lever in adjusted position.

5. In a gluing machine of the class described, the combination of a base having a pair of upright extensions formed with substantially vertical guideways, a rod having its ends disposed in said guideways, resilient means for mounting the ends of said rod, a glue tank having one end thereof mounted on said rod, a tank roller mounted on said tank, a gluing roller mounted on said base above said tank and adjacent said tank roller to receive glue therefrom, and means on said base for adjusting the height of the other end of said tank.

6. In a gluing machine of the class described, the combination of a base having a pair of upright lugs formed with substantially vertical guideways, a rod having its ends disposed in said guideways, resilient means for mounting the ends of said rods, a glue tank having one end thereof mounted on said rod, a tank roller mounted on said tank, a gluing roller mounted on said base above said tank in close proximity to said tank roller to receive glue therefrom, means on said base for adjusting the height of the other end of said tank, and a heater unit beneath said tank having one end supported on said rod and having its other end supported on said tank height adjusting means, said tank being removably mounted on said heater unit and said rod.

7. In a gluing machine of the class described, the combination of a base having a stop thereon, a glue tank, a tank roller mounted on said tank, a gluing roller mounted on said base in close proximity to said tank roller to receive glue there-

from, a feed roller in contact with said gluing roller, supporting means for said feed roller including an elongate arm pivotally mounted on said base, means for varying the effective length of said arm, an adjustable member on said arm for engaging said stop, means for pivotally mounting one end of said tank on said base, resilient means for supporting said last mentioned means on said base, and means on said base for adjusting the height of the other end of said tank.

8. In a gluing machine of the class described, the combination of a base having a stop thereon, a glue tank, a tank roller mounted on said tank, a gluing roller mounted on said base in close proximity to said tank roller to receive glue therefrom, a feed roller in contact with said gluing roller, supporting means for said feed roller including an elongate arm pivotally mounted on said base, means for varying the effective length of said arm, an adjustable member on said arm for engaging said stop, means for pivotally mounting one end of said tank on said base, resilient means for supporting said last mentioned means on said base, means on said base for adjusting the height of the other end of said tank, and drive means for effecting rotation of said tank roller and said feed roller including a fixed gear, gear means rotatable with said tank roller and meshing with said fixed gear, and gear means on feed roller support rotatable with said feed roller and meshing with said fixed gear.
